UNITED STATES PATENT OFFICE.

EDWARD H. ANGIER, OF FRAMINGHAM, MASSACHUSETTS.

METHOD OF WRAPPING TIRES AND THE LIKE AND MACHINE FOR PRACTISING THE SAME.

1,354,371.

Specification of Letters Patent. Patented Sept. 28, 1920.

Application filed November 25, 1916. Serial No. 133,437.

To all whom it may concern:

Be it known that I, EDWARD H. ANGIER, a citizen of the United States, and resident of Framingham, in the county of Middlesex and Commonwealth of Massachusetts, have invented an Improvement in Methods for Wrapping Tires and the like and Machines for Practising the Same, of which the following description, in connection with 10 the accompanying drawings, is a specification, like characters on the drawings representing like parts.

This invention relates to a method of wrapping articles and to a suitable machine by the use of which the method may be practised, and among other objects aims to provide means for quickly applying a strong, smooth wrapper.

The character of the invention may readily 20 be understood by reference to the following description of the illustrative machine shown in the accompanying drawings, which in its operation exemplifies the novel method of wrapping articles which forms 25 one part of my invention. In these drawings,—

Figure 1 is a front elevation of the machine showing certain parts in section;

Fig. 2 is a side elevation of the machine 30 shown in Fig. 1;

Fig. 3 is a vertical section taken on line 3—3 of Fig. 1;

Fig. 4 is a plan of the machine;

Fig. 5 is a horizontal section taken on 35 line 5—5 of Fig. 1;

Fig. 6 on an enlarged scale is a detail view showing a hand wheel and pawl and ratchet mechanism for elevating and lowering the dished presser plate;

Fig. 7 is a side elevation of parts shown 40 in Fig. 6;

Fig. 8 on an enlarged scale is a vertical section taken on line 8—8 of Fig. 1;

Fig. 9 is a transverse vertical section, on 45 an enlarged scale, through the article-supporting table and adjacent mechanism, the section being along a horizontal diameter viewing Fig. 5;

Fig. 9^a is a detail to be referred to;

Fig. 10 is a sectional detail of the tumbler-worm and its carrier in the transmission to the tire-supporting table;

Fig. 11 on an enlarged scale is a plan of the device for moistening the gummed wrapper strip shown in Fig. 2;

55

Fig. 12 is a side elevation of the parts shown in Fig. 11;

Fig. 13 on an enlarged scale is a plan of the wiper belt and its carrier;

Fig. 14 is a section through one of the 60 columns of the frame showing in plan a detail of the supporting means for the upper mold member;

Fig. 15 is a side elevation of parts shown 65 in Fig. 13;

Figs. 16 to 19 are views illustrating successive steps in the wrapping operation; and

Fig. 20 is a side elevation of a group of 70 tires completely wrapped by the machine.

While the method which forms one branch of my invention may obviously be practised independently of the particular mechanism here shown, it will conduce to brevity in this specification if I describe it in connection 75 with the manner of operation of the machine here disclosed. I shall, therefore, first describe that machine in order that its operation and consequently the method exemplified thereby may be abundantly clear.

The machine will be described in connection with its use for wrapping a group of tire shoes, although obviously its field of use is not restricted thereto. Characterized briefly, the operation of the machine chosen 85 as illustrating my invention is to wrap a sheet about one circumference and the ends of the group of tires, provision being made for conforming the wrapping sheet to the group, and to seal the package by a sealing 90 strip applied to the other circumference, the tires being compressed within the package to tension the wrapping.

Referring to the drawings, the machine shown herein as illustrating the invention 95 comprises a disk-like table 1 (Figs. 1 to 5) having radial fingers 3 arranged adjacent the periphery thereof and held in different positions of adjustment by bolts 5 entered through slots in said fingers. The latter 100 may be shifted in or out to vary the effective supporting area of the table to accommodate tire shoes or other articles of different sizes as desired. The table has a hub

journaled on the reduced end 7 of a vertical shaft 9 which has its lower end mounted in a sleeve 11 in the base 13 of the machine frame. The table shaft 9 is yieldingly supported by a helical spring 15 encircling a reduced portion of said shaft and confined between upper and lower collars 17 thereon.

Beneath the table a mold may be provided for folding a wrapper up about the lower portion of the shoes. This mold comprises a disk 19 having brackets 21 projecting radially therefrom and adjustably held thereto by bolts 23 entered through elongated slots in said brackets. Mounted on the upturned ends of the bracket are supporting fingers 25 preferably of resilient material which are adapted to engage a wrapper and fold the same up smoothly about the lower, outer surface portion of the shoe or group of shoes as more fully hereinafter described. The brackets and fingers form a skeletonized, cup-shaped mold which may be readily adjusted to accommodate tires or articles of different sizes. The mold has a hub 27 depending therefrom receiving the table shaft 9 and journaled in a bearing 29 on the frame base.

The table and mold are adapted to be rotated for a purpose more fully herein-after described. In Figs. 1, 5 and 9 is shown a suitable mechanism to accomplish this including a worm gear 31 secured to the under face of the mold and adapted to be driven by a tumbler-worm 33 (Fig. 10) fast on a shaft 35 journaled in bearings in a rocker bracket 37, which bracket is ful-crumed on a horizontal shaft 41 extending the length of and journaled in bearings in the machine base. The worm is driven by a pinion 43 on the shaft 35 which meshes with a pinion 44 in the shaft 41. At the left end (Fig. 5) of the shaft 41 is a gear 45 driven by pinion 47 of an electric motor 49 mounted on the frame base.

To rotate the mold and table at the times desired, the rocker bracket may be adjusted to throw the worm into or out of mesh with the worm gear. To accomplish this the bracket 37 may be connected by a link 51 (Fig. 5) with an eccentric pin 53 on the end of a shaft 55 journaled in brackets 57 on the machine base. At one end of said shaft is a handle 59 which may be readily rocked to shift the tumbler-worm to positions where it is effective or ineffective to impart rotation from the motor to the table and mold as desired.

The table 1 is normally urged upward away from the mold by its supporting spring. When in this position it is free to swivel on its supporting shaft to permit ready rotative adjustment of the table to facilitate positioning of articles thereon or for other purposes. When, however, the

table is pressed downward against the resistance of its supporting spring it should engage the mold so as to rotate therewith. To this end, the table and mold may be provided with interengaging lugs 61 (Figs. 70 9 and 9^a) adjacent their peripheries so that when they are brought in line with each other rotary movement of the mold will be positively imparted to the table. These lugs may be wedge-shaped as shown to prevent them from limiting downward adjustment of the table toward the mold.

After the tire-shoes have been placed on the table, they may be compressed or tensioned so that they may later expand and contribute to the tightness and smoothness of the wrapper. This compression is important, since during storage and shipment, packages of wrapped shoes may be stored in piles, and if not adequately preliminarily compressed the weight on the lower packages might loosen their wrappers, destroy the smoothness thereof and injure the same.

Means for compressing the tire shoes will next be described. To accomplish this an upper presser mold may be provided comprising a series of spring fingers 63 (Figs. 1, 2 and 3) secured to bars 65 radially disposed on a ring 67 and adjustably connected to said bars by bolts 69 projecting through elongated slots in said bars. These fingers may be readily adjusted to conform to tire shoes or other articles of different sizes. The ring 67 is connected to a second ring 71 and is spaced therefrom. Received between the two rings are rollers 73 carried by studs 75 of brackets 77 (Figs. 1 and 14). The two rings can thus rotate freely. The brackets 77 are bolted to guide fins 79 on nuts 81, said fins being adapted to slide in vertical slots 83 (Fig. 5) formed in tubular columns 85. These columns may have reduced ends 85^a set in sockets in the frame base 13 as shown at the left of Fig. 1, and the upper ends of the columns have heads 86 (Figs. 1 and 4) connected by a horizontal bridge 87.

For lowering and raising the presser mold, screw shafts 88 receiving the bracket carrying nuts 81 may be mounted in said tubular columns and have their upper ends journaled in said heads, and projecting beyond the same to receive gears 89 (Figs. 1, 4 and 8), the hubs of which are mounted fast on said shafts and confine the latter against downward movement in said columns. The gears 89 mesh with pinions 91 on stud shafts 93 journaled in said heads 86 and having bevel gears 95 on their upper ends meshing with bevel gears 97 on a horizontal shaft 99 journaled in brackets 101. The shaft 99 projects beyond one of said brackets and has pulleys 103 and 105 (Figs. 1 and 4) loose thereon and an intermediate pulley 107 fast thereon. The pulley 103 is 130

connected by a belt 109 with a pulley 111 (Fig. 1) fast on the motor driven shaft 41 referred to. The pulley 105 is connected by a crossed belt 113 with said pulley 111. Thus the intermediate pulley 107 may be driven in opposite directions depending on whether the belt 109 or the belt 113 is shifted thereto.

To control the belts a shipper is provided 10 comprising belt engaging portions 115 on a slide 117 shiftable axially in brackets 119 on said bridge. The shipper is connected to an arm 121 depending from a rock shaft 123 journaled in brackets projecting from 15 one of the column heads 86. An arm 125 fast on said shaft carries a depending rod 127 having a handle 129. When this handle is pulled downward it will move the shipper slide 117 to the left of Fig. 1 and throw the 20 crossed belt 113 on the intermediate pulley 107 to rotate the shaft 99 and the screw shafts 88 and cause the upper mold to move down toward the group of shoes on the table. When the upper mold has moved 25 downward sufficiently to apply the desired degree of compression to the shoes, the handle 129 may be moved upward, thereby shifting the belt 113 from the tight pulley 107 to its loose pulley 105, and thus arresting 30 further downward movement of the mold.

When it is desired to elevate the mold and release the compression, the handle 129 may be shifted farther upward, thereby adjusting the shipper 115 farther to the right and 35 throwing the uncrossed belt 109 to the tight pulley 107. This will rotate the shaft 99 and the screw shafts 88 in the opposite direction and cause the presser mold to move upward away from the group of shoes. When the mold has traveled upward sufficiently 40 the handle 129 may be pulled downward, thereby shifting the belt 109 to the left to its loose pulley and causing the arrest of the mold.

Means may be provided for automatically 45 arresting the presser mold at the limits of its travel to relieve the operator from the burden of watching the mold and arresting the same at the proper time. To this end 50 the shaft 123 which controls the shipper may have an arm 131 (Figs. 1 and 4) fast thereon from which hangs a rod 133 which passes through a hole in an arm 135 (Fig. 1) projecting laterally from one of the supporting 55 brackets 77 of the upper presser mold referred to. The rod 133 may carry upper and lower stop collars 137, and when the presser mold travels downward its arm 135 will slide along the rod 133 until it engages 60 the lower stop collar 137. A slight further downward movement of the mold will drag the rod 133 downward, thereby shifting the belt 113 to the right from the tight pulley 107 to its loose pulley 105 and arresting the 65 further downward movement of the mold.

On the other hand, when the mold travels upward, its arm 135 will slide along the rod 133 until it engages the upper stop collar 137. Slight further upward movement will shift said rod upward and shift the belt 70 109 from the fast pulley 107 to its loose pulley 103.

By the mechanism described the presser mold may be shifted upward or downward by power and automatically arrested at the 75 limits of its travel. In some cases it may be desired to move the presser mold manually or it may be desired to adjust said mold manually as an operation supplemental to the power driven movement thereof. To accomplish this the gear 89 at the top of the screw shaft at the left of Figs. 1 and 4 may mesh with a pinion 139 fast on a shaft 141 journaled in an upper bearing 143 on one of the column heads 86, and in a lower bearing 85 in a bracket 145 projecting laterally from said column. The lower end of said shaft carries a bevel gear 147 which meshes with a bevel gear 149 on a stud shaft journaled in said bracket 145 and having a hand wheel 90 151 fast thereon. By turning said hand wheel rotary movement may be imparted through the shaft 99 and the bevel gears 95 and 97 to the screw shafts 88, thereby moving the presser mold up or down as desired. 95

When this manual operation is being performed, of course the belts 109 and 113 should be on their loose pulleys so that they will be inoperative to transmit motion to the shaft 99.

In the course of the wrapping operation 100 it is desired to release the presser mold to allow the wrapper to be spread over the surface covered by said mold. To hold or clamp the group of shoes compressed during 105 this operation, suitable means may be provided typified herein as a dished plate 153 (Figs. 1, 2 and 3) having fingers 155 projecting radially therefrom and adjustably connected thereto by bolts 157 entered 110 through elongated slots in said fingers. The latter may be adjusted out or in to accommodate shoes or other articles of different sizes. These fingers are adapted to engage the inner, upper surface portion of the top shoe 115 substantially as shown in Fig. 18. To control the clamp plate it may be swiveled on the reduced end 159 of a rack bar 161 adapted to slide, but not rotate in a central boss 163 of the bridge 87.

Said clamp plate is raised and lowered by a pinion 165 (Figs. 1, 4 and 8) on a horizontal shaft 167 journaled in bearings in said bridge. A bevel gear 169 fast on one end of said shaft meshes with a bevel gear 171 fast 125 on an end of a horizontal shaft 173 journaled in brackets 175 (Figs. 1 and 4) projecting laterally from said bridge. A bevel gear 177 on the opposite end of shaft 173 meshes with a bevel gear 179 fast on a 130

vertical shaft 181 journaled in an upper bearing in the head 86 of the right-hand column in Fig. 1 and in a lower bearing in a bracket 183 (Figs. 6 and 7) projecting 5 from said column. To rotate the shaft 181 a bevel gear 185 thereon meshes with a bevel gear 187 on a stud shaft journaled in said bracket and carrying a hand wheel 189 (Figs. 1, 2, 3, 6 and 7).

- 10 When the hand wheel 189 is rotated in one direction it will operate through the gearing described to rotate the rack pinion 165 and rapidly lower the clamp plate rapidly toward and into engagement with the top shoe 15 of the group of shoes. To secure and hold the clamp plate in this position, a pawl 191 is pivotally mounted on the bearing of the hand wheel shaft and is adapted to engage a ratchet wheel 193 fast on the hub of the 20 hand wheel. This will lock the hand wheel against reverse rotation and securely hold the clamp plate in position. When it is desired to release the clamp plate a handle 191^a on the pawl is rocked to trip the latter 25 from its ratchet wheel and then the hand wheel may be readily rotated in a reverse direction to elevate the clamp plate.

To facilitate the raising and lowering of the clamp plate a cable 195 may be secured 30 to a pin 197 on said plate, lead upward over a guide pulley 199, thence extend outward over a guide pulley 201 and, depending therefrom, pass through an eye of a counterbalance weight 203. The cable passes thence 35 through another eye (Fig. 4) on said weight and up over similar pulleys 205 and 207 and downward and its opposite end is secured to the pin 197 referred to. The clamp plate is thus effectively counterbalanced so that it 40 may be easily and quickly elevated and lowered as required.

The mechanism already described operates, as will be more fully explained herein-after, to wrap a sheet about the inner circumference and ends of the group of tires, folding the ends over toward each other at the outer circumference of the group. To complete the wrapping and to seal the package, means may be provided for wrapping a 45 strip of gummed paper or other suitable material circumferentially about the group of shoes to unite the ends of the wrapping sheet of the group.

Herein this means comprises a bracket 209 50 (Figs. 2, 5, 11 and 12) having a spindle 211 rising therefrom for receiving a spool 213 of gummed paper 214. The strip of paper may be led from the spool over a moistening device to the group of shoes. This moistening device comprises a cylinder 215 mounted 55 on the bracket 209 and containing waste 216 saturated with water. To moisten merely the margins of the gummed strip the cylinder may, as shown in Fig. 12, have sections 60 removed from a wall thereof to leave upper

and lower apertures 217. A pad 219 of felt or other suitable material may cover the apertures to prevent escape of the waste therethrough.

Presser rolls 221 may be mounted on an eccentric shaft 223 adjacent the moistening cylinder and opposite the apertures therein to facilitate proper guidance of the gummed strip. This shaft may have a handle 225 fast thereon for turning the rolls to vary 75 the space between the latter and said moistening device to produce the appropriate pressure of the strip against the moistening device. The eccentric shaft may be held in its different positions of adjustment 80 by a set screw 227 threaded in the bearing of the shaft.

To press the gummed strip against the package and insure secure adhesive engagement of said strip with the end of the wrapping there may be provided wiper belts 229 (Figs. 4, 5, 13 and 15) of felt or other suitable material and of a width corresponding to that of the moistened margins of the strip. These belts may have ends fastened 90 to a roller 231 journaled on a shaft 233 mounted on the machine base. The opposite free ends of said belts may be connected to a rod 234 having an eye 235 adapted, when the belts are not in use, to be hooked 95 over a pin 236 (see at the right of Fig. 4) projecting laterally from a post 237 on the machine base. When the wiper belts are in use they are released from the pin 236, the belts are unwound from the roller and the eye 235 is hooked over a pin 239, (at the left of Fig. 4) projecting laterally from a post 241 rising from the bracket 209 and which is at the opposite side of the machine 100 from the post 237 (see also Figs. 11 and 12). 105 To tension the wiper belts and automatically rewind the same on the roller 231 after they have been used to press the gummed strip against the package, a cord 243 (Figs. 2, 3 and 15) may have one end 110 connected to a spool 245 fast on the roller 231. The cord may be guided from said spool over a pulley 247 and have its opposite end attached to a weight 249. When the wiper belts are unwound from the roller 115 231, the cord 243 will be wound on the spool 245 and the weight will be lifted. When the wiper belts are released from the pins 239, the weight will unwind the cord from the spool and rewind said belts on said 120 roller.

To facilitate opening of the package to release the tires, a pull cord may be applied to the gummed strip. To accomplish this an arm 250 (Figs. 4 and 5) is provided 125 on the machine base adjacent the gummed strip roll and supports a holder 250^a for a ball of twine. The twine from this ball may be led up between the moistening device (Fig. 12) and the eccentric roll shaft. 130

Thence it may be drawn with the gummed paper to the package.

The operation of the machine which exemplifies my improved method of packaging tires and like articles, is as follows:

First a core or sleeve *a* (Fig. 16) of stiff paper or other suitable material is placed upon the table 1. Then a wrapping in the form of a tube of paper *b*, preferably 10 crimped or otherwise formed to permit differential contraction or expansion to conform to the shape of the article wrapped, is drawn down over said core with its lower end portion spread out on the surface of the 15 table 1. The upper end of the tube may be contracted by a rubber band *c* or other fastening applied thereto to prevent said end from being in the way of the next operation.

20 The shoes *d* to be wrapped are then placed on the table over said core and wrapping tube. The wrapping sheet at this stage covers the inner circumference of the group and extends outwardly over the lower end 25 surface but is not wrapped about the same. The crimpings of the sheet are opened out locally to permit a portion of the sheet to expand relatively to the rest and conform to the dimensions of the group of shoes.

30 Next the handle 129 is pulled to shift the belt 113 to the tight pulley 107, thereby rotating the screw shafts 88 and causing the presser mold 63 to travel quickly down toward and to the top shoe of the group of 35 shoes. The presser mold will continue on downward and compress the shoes until its arm 135 engages the stop collar 137 and draws the rod 133 downward to shift the belt and stop further movement.

40 In the course of the compression of the group of shoes, the table 1 will be depressed downward against the resistance of its supporting spring 15 into the lower mold 25 (Fig. 17). As a result, the outwardly projecting lower end portion of the wrapping tube will be folded and pressed by the fingers 25 of said lower mold up against the outer surface of the lower tire shoe.

Since the presser mold is of ring form it 50 will allow the contracted end of the paper wrapping tube to project upward therethrough without interference therewith. The clamp plate 153 will not interfere with the tube since it was previously adjusted 55 up out of the way.

The rubber band is then removed from the contracted end of the paper wrapping and said end is spread out over the presser mold. The hand wheel 189 is rotated 60 quickly to lower the clamp plate 153 toward the group of shoes and into the upper end of the wrapping tube. It continues on downward thereby causing its fingers 155 to press the wrapping tube against the inner, upper surface portion of the top shoe

(Fig. 18). It is now in position to relieve the presser mold from the work of holding the shoes compressed.

Next the belt shipper handle 129 is shifted to lift the presser mold up away from the 70 shoes toward the bridge, where it will be automatically arrested as described.

Then the wrapping tube is spread out over the outer, upper surface of the top shoe and the presser mold is again lowered there- 75 to (Fig. 19). Its fingers 63 will fold and press the wrapper tube down into intimate engagement with the outer surface of the upper shoe.

The wrapper now covers the group of 80 shoes with the exception of an exposed, circumferential portion between the upper and lower ends of the wrapper. To cover this the operator grasps an end of the gummed strip and draws the same from its supply 85 spool, the strip being automatically moistened and the pull cord applied thereto by the moistening device as the strip is drawn from said spool. The end of the strip is then stuck to the wrapper; the wiper belts 90 are unwound from the roller and their ends attached to the pin 239; and then the handle 59 is rocked to shift the worm 33 into engagement with the worm gear 31. This initiates rotation of the table and the rotation thereof continues until the gummed strip completely encircles the package. The wiper belts engage a substantial portion of the circumference of the package and exercise their pressure on the gummed tape for 95 a sufficient length of time to allow the strip to adhere securely to the end wrapping. However, merely a short time is required since a quick drying gum is used on the strip.

100 Merely the margins of the gummed strip are moistened in order that the portion thereof intermediate said margins may not adhere to the shoes.

In some cases the wrapping tube may be 110 made of sufficient length so that its end portions may meet or overlap and complete the closure without the necessity for employment of the gummed strip described, although it is preferable to use the latter 115 since it contributes to the production of a stronger wrapping and one which is more finished in appearance.

120 After the wrapping of the group of shoes is completed, the clamp disk and upper presser mold are lifted up away from the group of shoes, thereby permitting the table-supporting spring to elevate the table to a point where it is substantially level with the free ends of the fingers 25 of the lower 125 mold. The wrapped package with its core may then be slid from said table and the core removed.

130 The machine described will wrap the paper tightly about the group of shoes, and

the tendency of the shoes to expand upon release of their compression will further contribute to the tightness of the wrapping.

Various wrapping materials may be employed, but a very desirable wrapping may comprise sheets of paper having a layer of adhesive, black asphaltum between them in which reinforcing strands are embedded as shown in my copending application, Serial 10 No. 131,789, filed Nov. 16, 1916. The threads desirably extend longitudinally of the tube which is formed from the wrapping sheet and take the strain of the compressed tires.

From the description of the operation of 15 the machine disclosed, the novel method of wrapping articles which is a part of my invention and which the machine illustrates has been rendered clear. It is necessary to point out here only that, while the machine 20 disclosed is a convenient and desirable appliance for practising the method, the method, may be practised by hand or with the aid of other mechanisms or appliances. Briefly stated the method contemplates 25 wrapping an article by applying sheet covering material to the ends of the article, conforming thereto and presenting opposed ends at the sides and connecting said ends by a circumferentially disposed strip. More 30 explicitly to describe the particular manipulative steps here disclosed as an example of the method, it may be practised by applying a sheet *b* to one circumference of an annular article; folding the ends of the sheet over 35 the ends of the article and toward the other circumference, the sheet being conformed to the article by differential expansion, for example, by local expansion or contraction of suitable crimpings, and connecting the 40 opposed ends at said other circumference.

Heretofore considerable difficulty has been experienced in wrapping and properly protecting tire shoes and other articles during 45 shipment and storage, but by my invention such articles may be quickly covered with a strong, protective, permanent wrapping of smooth, finished appearance.

While the machine has been described more particularly with reference to its use 50 in wrapping tire shoes and like annular articles, it will be understood that the forms of the upper and lower molds may be varied and the machine may wrap various other articles as desired.

Having described one illustrative embodiment of my method and one suitable machine for practising the same, without limiting my invention thereto, what I claim as new and desire to secure by Letters Patent 60 is:

1. In a machine of the class described a pair of relatively movable concaved members adapted to fit over the ends of an article and hold wrapping material thereabout, a

strip supply and means for effecting relative movement of revolution between said member about an axis connecting the ends of said article and said supply whereby a connecting strip may be drawn around the article between the ends to secure such 70 wrapping material.

2. In a machine of the class described a pair of relatively movable concaved members adapted to fit over the ends of an article and hold wrapping material thereabout, a 75 strip supply and means providing for bodily rotation of said members about an axis extending in the direction of compression whereby a connecting strip may be drawn around the article between the ends 80 to secure such wrapping material.

3. In a machine of the class described an article support having means for rotating the same, an opposed plunger having a rotatably-mounted, work-engaging face and 85 means to move the same toward and from the support in the general direction of the axis of rotation.

4. In a machine of the class described a cup-like article receiver having means for 90 rotating the same, a displaceable support normally positioned adjacent the top of the cup, an opposed plunger having a rotatably-mounted, work-engaging face and means to move the same toward and from the support 95 in the general direction of the axis of rotation.

5. In a wrapping machine an article support having upturned marginal portions adapted to wipe along the sides of an article 100 to fold wrapping material thereover, an opposed presser acting substantially in line with the bases of said portions whereby to effect smooth folding, and pressure-retaining means acting on the article inwardly of 105 the margins to permit withdrawal of the presser.

6. In a machine of the class described means for holding an article by its ends and for holding wrapping material folded over 110 said ends with edges presented in opposition, strip supply means, means for applying liquid to the strip on either side of the center whereby to permit adhesive sealing of the same to said edges and means to apply a pull cord to the strip between the moistened zones.

7. In a machine of the class described an article support, an opposed annular presser, laterally disposed means for moving the 120 presser and an inner pressure-retaining device disposed within the outline of the presser, and means for moving it alternatively with the first.

8. In a machine of the class described an 125 article support, an opposed annular presser, laterally disposed screw shafts for raising and lowering the presser, an inner pressure-

retaining device disposed within the outline of the presser and a quick action device for raising and lowering the same.

9. A constituent element of a wrapping machine, as described, comprising a press element having angular, radially extending and radially adjustable elements marginally secured thereto.

10. In a wrapping machine a frame-like compression member, a second compression member within the limits of said frame and means to operate the two in alternation.

11. In a wrapping machine a frame-like compression member of angular section adapted to engage the peripheral edge of the article wrapped, a second compression member within said frame and means to operate the two in alternation.

12. In a wrapping machine for annular articles, a ring-shaped mold to engage the exterior periphery of an article on one side thereof, a circular mold within the same adapted to engage the interior circumference of the article and means for moving each axially of the article to be wrapped.

13. A machine for wrapping articles comprising in combination, a support for an article, means to rotate said support, means to supply a gummed wrapping strip thereto, means to moisten said strip, a roller, a wiper belt for pressing said strip against the article as it is rotated, a roller for said belt, and means for automatically winding the latter on said roller.

14. A machine for wrapping articles comprising in combination, a support for an article, means to supply a gummed strip thereto, and means for moistening said strip comprising an apertured water container and eccentric means for guiding said strip past said container.

15. A machine for wrapping articles comprising in combination, a support for an article, means to supply a gummed strip thereto, a roller, a belt adapted to be wound on said roller, means to hold said belt in inoperative position, means to hold said belt in position to press said belt against the article, and means to rotate said support to wind said strip between said belt and said article.

16. A machine for wrapping articles comprising in combination, means for positioning opposed end wrappings over an article and along the sides thereof, means to apply a binding strip to said wrapping, and means to apply a pull opener cord between said strip and the article.

17. A machine for wrapping articles comprising in combination, means for positioning opposed end wrappings over an article and along the sides thereof, means to apply a moistened gummed strip to said wrapping, and means to apply a pull opener cord to the gummed face of said strip.

18. A machine of the class described comprising a rotatable support, means for driving the same, means for positioning covering on an article carried by said support, a pair of elements lying in a line which forms a secant relatively to an article on the support, and a wiper belt having an end attached to one of the elements and having provision whereby it may be yieldingly extended between said elements and bear on the article in its rotation.

19. In a machine of the class described means for pressing wrapping material about an article comprising a flexible band resiliently extended and adapted to be displaced by the article to bear on the same along an extended length and means for causing relative rotation between said band and the article.

20. In a machine of the class described means to rotate an article and a wiper comprising a band adapted to be resiliently extended tangentially across the orbit of said rotating means and to be displaced therefrom by the article.

21. In a machine of the class described a strip supply, an article support, means to effect revolution of one relative to the other to draw strip from the supply to the article, a flexible band mounted adjacent the article and means to draw it into yielding intimate contact with the article in advance of the point of application of the strip thereto.

22. A method of wrapping annular articles and the like characterized by inserting a longitudinally crimped tubular sheet through the hole of an article, folding and spreading end portions of the sheet tightly about the ends of the article, then wrapping a circumferential band about the outer surface of the article over the end portions of the tubular sheet and securing the band marginally to said sheet and applying a cord beneath said band between the lines of attachment.

23. A method of wrapping annular articles comprising the following steps: applying a sheet to one circumference of an article, folding the ends of the sheet over the ends of the article and toward the other circumference by pressing the same along spaced radii, said sheet being conformed to the article by differential crimping thereof, and connecting said ends at the other circumference of the article.

24. A method of wrapping annular articles characterized by forming a tube of expansible material, inserting the tube in the hole of the article, compressing the article, expanding end portions of the tube over the ends of the article, connecting said end portions, and then releasing the compression to permit the article to tension the material.

25. A method of wrapping elastic things

- characterized by the following steps:—compressing the same by locally applied pressure, clamping wrapping material thereto at an adjacent location, releasing the first pressure while maintaining the thing under compression by the clamping pressure and spreading the material over the locality where said first pressure was applied.
- 5 26. A method of wrapping elastic things characterized by the following steps:—compressing the same by locally applied pressure, clamping wrapping material thereto at an adjacent location, releasing the first pressure while maintaining the thing under compression by the clamping pressure and again exerting said first pressure to spread the wrapping material over the locality of its initial application.
- 10 27. A method of wrapping elastic things characterized by the following steps:—compressing the thing by pressure applied about the periphery thereof, applying a retaining pressure inwardly of the periphery and releasing the first pressure to permit the application of covering about the periphery of the compressed thing.
- 15 28. A method of wrapping elastic things characterized by the following steps:—compressing the thing by pressure applied at the periphery of an end thereof, clamping wrapping material to said end by a retaining pressure applied thereto, releasing the first pressure and folding the wrapping material over said end.
- 20 29. A method of wrapping elastic things characterized by the following steps:—compressing the thing by a pressure member fitting over an end thereof, clamping wrapping material to said end by a retaining pressure applied thereto inwardly of the edges thereof, removing said member and again applying it to fold said material over the end.
- 25 30. A method of packaging elastic annular things characterized by the following steps:—assembling the thing with wrapping applied about a circumference thereof, compressing the thing by endwise pressure applied to the other circumference, folding the material over the end of the compressed article, applying retaining pressure at said first circumference and to the material, releasing said first applied pressure and joining the wrapping along said other circumference.
- 30 31. A method of packaging elastic annular things characterized by the following steps:—assembling the thing with wrapping applied about a circumference thereof, compressing the thing by endwise pressure applied to the other circumference by a member having portions extending over said other circumference, folding the material over the end of the compressed article, applying retaining pressure at said first circumference and to the material, removing said member, again applying said member to fold the material over said other circumference, joining the material along said other circumference and releasing all pressure.
- 35 32. A method of wrapping elastic annular things characterized by the following steps:—compressing the thing by applying to an end thereof a pressure member having a portion extending over one circumference thereof, clamping wrapping material to the end of the article and the other circumference by a pressure member fitted thereto, retaining pressure on the thing by said second member, removing said first member and again applying it to fold said material about the thing.
- 40 33. A method of packaging elastic annular things characterized by the following steps:—compressing the thing by applying pressure at the periphery thereof, clamping wrapping material to the ends thereof by means retaining pressure on the thing, said material having outwardly presented edges, releasing the peripheral pressure joining said edges circumferentially about the thing and releasing all pressure thereby permitting the thing to expand and tension the wrapping.
- 45 34. The method of wrapping annular articles comprising holding the article adjacent one circumference, folding a strip encircling the other circumference over toward the first, holding said other circumference and releasing the first, and finally folding the strip over said first circumference.
- 50 In testimony whereof I have signed my name to this specification.
- EDWARD H. ANGIER.
